[57] CLAIM

The ornamental design for an input/output terminal, as shown and described.

DESCRIPTION

FIG. 1 is a top plan view of the input/output terminal showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a perspective view thereof on an enlarged scale.
